UNITED STATES PATENT OFFICE.

GEORGE E. SAVAGE, OF MERIDEN, CONNECTICUT, ASSIGNOR TO MANNING, BOWMAN & CO., OF SAME PLACE.

DESIGN FOR A CHAFING-DISH STAND.

SPECIFICATION forming part of Design No. 35,139, dated October 1, 1901.

Application filed July 22, 1901. Serial No. 69,337. Term of patent 7 years.

To all whom it may concern:

Be it known that I, GEORGE E. SAVAGE, of Meriden, in the county of New Haven and State of Connecticut, have invented and produced a new and original Design for a Chafing-Dish Stand; and I do hereby declare the following, when taken in connection with the accompanying drawing and the letters of reference marked thereon, to be a full, clear, and exact description of the same, and which said drawing constitutes part of this specification and represents a view in perspective of a chafing-dish stand embodying my design.

This invention relates to a design for a chafing-dish stand; and the design consists in the configuration and ornamentation as herein described and shown in the accompanying illustration.

As herein shown, the design consists of a chafing-dish stand comprising a ring A, sup-

ported upon three bowed legs B, tapering from their upper to their lower ends and having the convex outer faces of their upper ends provided with rococo ornamentation in relief, comprising two conventional sprays C, 25 depending from a central shield-and-shell motive D, the whole ornament being of horse-shoe shape in general outline, all as shown in the accompanying illustration.

I claim—

The design for a chafing-dish stand, as herein described and shown in the accompanying illustration.

In testimony whereof I have signed this specification in the presence of two subscr- 35 ing witnesses.

GEORGE E. SAVAGE.
